(57)

CLAIM

The ornamental design for a waved zipper pull as shown and described.

DESCRIPTION

FIG. 1 is a front isometric view of a waved zipper pull showing my new design;

FIG. 2 is a front elevation view thereof;

FIG. 3 is a left side elevation view thereof;

FIG. 4 is a rear elevation view thereof;

FIG. 5 is a right side elevation view thereof; and

FIG. 6 is a top plan view thereof;

FIG. 7 is a bottom plan view thereof; and,

FIG. 8 is a front isometric view of the waved zipper pull on a zipper.

(Continued)

The broken lines showing of the zipper is for the purpose of illustrating how the waved zipper pull is positioned and forms no part of the claimed design.

1 Claim, 8 Drawing Sheets
